LINUS YALE, JR., OF COOPERSTOWN, NEW YORK.

Letters Patent No. 73,152, dated January 7, 1868; undated December 21, 1867.

IMPROVEMENT IN VISSES.

The Schedule referred to in these Letters Patent and making part of the same.

TO ALL WHOM IT MAY CONCERN:

Be it known that I, LINUS YALE, Jr., of the town of Cooperstown, in the county of Otsego, and State of New York, have invented certain new and useful Improvements in Vises; and that the following, taken in connection with the drawings, is a full, clear, and exact description thereof. In the drawings—

Figure 1 is a side elevation of a vise.

Figure 2 is a section through the same, exhibiting my improvements.

Figure 3 is another section with the travelling-nut in a different position; and

Figure 4 is an elevation of the contrivance for retaining the screw in the movable jaw.

My improvements are applicable to various kinds of vises. The drawings exhibit them as applied to a parallel vise. And my improvements consist,

First, in a contrivance for throwing the nut into and out of a working position, or a position in which the revolution of the screw will open and close the jaws, by means of an inclined plane on the exterior of the nut, in combination with an inclined plane attached to the moving jaw.

Second, in a combination of a screw and a nut, with inclined planes and a rack, by means of which the moving jaw can be freed from control of the screw, and moved in and out rapidly without any movement of the screw, and can also be forced to submit to the control of and be moved by the screw.

These improvements have the effect of rendering the vise adaptable with great facility to articles of varying size, and thereby save much time, and also permit the use of a comparatively short screw-thread, while at the same time the vise has a long range of motion. My improvements consist,

Thirdly, in the combination of a spring with the nut, screw, and stationary and moving jaws of a vise, in such manner, substantially as hereafter described, that articles may be grasped in the jaws, either by the force of the spring, or by the whole power of the screw, and this improvement is of great use where articles are to be filed to a pattern, as the pattern and piece to be filed can be adjusted to each other with great ease and quickness. And my

Fourth improvement is a contrivance, which I term a sectional collar, by means of which the screw of a vise is attached to the sliding jaw in such manner that the latter follows the movements of the former in the direction of its axis.

In the drawings, the stationary jaw of the vise is shown at *a a a*, and the screw by which it is attached to the bench at *b*. The moving jaw is represented at *c c c*, and is provided with a screw, *d*, fitted with a proper head and sliding hand-lever, as usual. This screw is fitted with a collar, *e*, whose inner and outer peripheries lie in recesses formed in the screw and the moving jaw. This collar is made in pieces, as shown in fig. 4, which are introduced one by one through the opening closed by the screw *f*. This collar causes the jaw to move with the screw, and *vice versa*. The screw-shank is also, as usual, provided with a shoulder, which bears against a shelf or projection formed in the moving jaw at *p*. The moving jaw has a hollow or long cavity formed in it, to contain the screw and the nut, and this cavity is sufficiently large to permit the screw to rock slightly up and down in it, and is open at the bottom, so as to permit the nut to take hold of a rack. The screw enters a nut, *g*; and this nut is bevelled, or has inclined planes on the top and bottom thereof, substantially such as are represented in figs. 2 and 3, and is likewise racked on its lower surface. The cavity of the jaw is also formed with corresponding inclined planes, or surfaces *h i*, inclined to the plane of the rack. A rack or notched bar, *k*, is attached to or makes part of the lower jaw, and projects upward, so that its teeth may engage with corresponding teeth on the lower surface of the nut.

The operation of these parts is as follows: When the parts are in position, as shown in fig. 3, any article may be placed between the jaws, and gripped by turning the screw, as in an ordinary vise, the nut being at the time stationary, and kept stationary by the engagement of its teeth with the rack-teeth. The grip may be relaxed also in the same way, and after it has been relaxed and the article removed, a revolution of the screw to open the jaw will eventually compel the nut to rise up on the inclined plane *i*, thereby disengaging the racks from each other, and putting the parts in the position shown in fig. 2. When the parts are in this position, the moving jaw can be slid in and out by hand, without turning the screw, and brought with great rapidity to a position to admit into the vise the next article to be grasped. When such article is introduced between the jaws,

the moving jaw is to be brought in contact, or nearly in contact, with it, by sliding it by hand. The screw is then to be turned in the direction for causing the sliding to approach the stationary jaw, and this turning of the screw will draw the nut over the inclined planes, the upper plane, *h*, forcing the nut into engagement with the rack. As soon as the nut is engaged, a further revolution of the screw will cause the sliding jaw to approach and grasp the article to be held. After the article is released, a revolution of the screw, to relax the grasp of the vise, will again throw the nut out of engagement with the rack, permitting the sliding or moving jaw to be moved freely by hand, without turning the screw.

I intend, at times, to dispense with the upper inclined planes, and permit the nut to drop by the force of gravity, and at others to locate a spring between the top of the nut and the top of the cavity of the moving jaw, which shall always tend to depress the nut, thereby keeping the lower inclined planes of both the nut and jaw in contact, when the one is opposite the other. At other times, I intend to apply a spring to the nut, tending to draw or throw it upwards, and in that event to use the upper and dispense with the lower inclined plane, the nut being then held down in engagement with the rack, when necessary, by the bearing of its upper face against the top of the cavity, as shown in fig. 3. But in all cases there must be at least one inclined plane upon the nut, and one upon the moving jaw, or some equivalent thereof, such, for instance, as a pin projecting from the one into a groove formed in the other.

The improvements thus far specially described, by reference to a parallel vise, are equally applicable to those kinds of vises in which the moving jaw turns upon a pivot, and although I have, up to this point, considered the rack as immovable with respect to the stationary jaw, and so intend to use it in combination with the travelling-nut, yet it will be perceived that the rack shown in the drawings is not fastened immovably to the stationary jaw, but, on the contrary, is attached to it in such manner that it can slide along, or vary its position with respect to the jaw, being held down by a screw, *n*, the head and shank of which are free to slide in a cavity in the jaw, and being forced towards the hinder end of the jaw by a spring, *m*, bearing at one end upon the stationary jaw, and at the other upon a pin or piston abutting against a hook depending from the rack. In those modifications of this contrivance in which an inclined plane on the upper side of the nut is used, it may sometimes happen that the edges of the racks will ride and jam when the nut is descending, thus causing delay consequent upon a resetting of the parts, and one use of the spring is to obviate this difficulty, which it does by permitting the rack to start forwards, so that both sets of teeth may engage fully, but the chief use of the spring remains to be described. When the sliding jaw is forced upon any article or articles by means of the screw, such a grasping will compress the spring, and the article will at first be held between the jaws merely by the power of the spring. While thus held, the article or articles may be removed or changed in position with respect to each other or to the jaws, the force of the grasp being diminished, if necessary, by pulling upon the sliding jaw without turning the screw. When the article or articles are properly located with respect to each other or to the jaws, or both, then the screw is to be turned, and its revolution will draw the rack along the stationary jaw, until the hook attached to it bears against that jaw, and the rack ceases to move. After that, the jaws may be caused to approach each other by the whole power of the screw. The result of the contrivance is, that articles can be grasped either by the force of the spring, or by the whole power of the screw, and this result does not follow from any special kind of spring, nor from any precise location thereof, so long as it is so located that the spring shall be compressed by the revolution of the screw, after the moving jaw is in contact with the article being grasped.

The various parts of this invention may be used out of connection with other parts.

I claim as of my own invention—

1. A screw capable of operating the moving jaw of a vise, in combination with a nut having an inclined plane thereon, and an inclined plane attached to the moving jaw, these parts being and operating in combination, substantially as described.

2. In combination with a rack attached to the stationary jaw of a vise, and an inclined plane attached to the moving jaw thereof, I claim a racked nut, provided with a screw, and an inclined plane, the combination being substantially such as described, and operating substantially as set forth.

3. In combination with the jaws of a vise, a screw, a rack, and a racked nut, I claim a spring, located as described, and operating in combination with the parts with which it is combined, substantially as described, to control the position of the rack, substantially in the manner and for the purpose specified.

Lastly, I claim a sectional collar, in combination with a moving vise-jaw, and the screw which operates it by means of recesses therein, the combination being and operating substantially as hereinbefore set forth.

In testimony whereof, I have hereunto subscribed my name.
